UNITED STATES PATENT OFFICE.

EDNA F. MEIER, OF DENVER, COLORADO.

CHILD'S WAIST.

1,385,221.

Specification of Letters Patent. Patented July 19, 1921.

Application filed September 16, 1918. Serial No. 254,275.

To all whom it may concern:

Be it known that I, EDNA F. MEIER, a citizen of the United States, residing at the city and county of Denver and State of Colorado, have invented certain new and useful Improvements in Children's Waists; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in waists for children, my object being to provide a device of this character which is of such construction as to prevent the pulling off of buttons in the back as the child stoops.

20 Heretofore, so far as I am aware, waists have been made which are rigid or non-elastic in the back so that in the case of a child wearing a waist and trousers, the trousers buttoning upon the waist, as soon

25 as the child bends forward there is an undue strain on the back buttons of the waist which results in pulling off these buttons at frequent intervals, thus causing a relatively large amount of trouble due to repair work

30 and general annoyance.

My improvement is intended to overcome this difficulty and to this end I provide a yieldably retained vertical fold or plait extending transversely across the back of the 35 waist, preferably just above the zone or area where the buttons are located. The specific construction is immaterial so long as the object is attained.

As illustrated in the drawing, I provide 40 a fold or plait in the back of the waist and connect elastic strips with the waist both above and below the plait or fold so that normally the plait is closed. When the child stoops or bends forward these elastic strips 45 will yield and the fold or plait will extend as necessities require, thus relieving the buttons from undue strain.

Having briefly outlined my improvement, I will proceed to describe the same in detail, 50 reference being made to the accompanying

drawing in which is illustrated an embodiment thereof. In this drawing:

Figure 1 is a rear view or elevation of a child's waist, provided with my improvement.

Fig. 2 is a section taken on the line 2—2, Fig. 1, the parts being shown on a larger scale.

Fig. 3 is a rear view showing the waist in position upon a child.

Fig. 4 is a side view of the same.

Fig. 5 is a view similar to Fig. 4, but showing the child in the stooped or forwardly bent position, the yielding quality of the waist being indicated.

The same reference characters indicate the same parts in all the views.

Let the numeral 5 designate a child's waist provided with buttons 6 for the trousers and other buttons 7 for the undergarment. This 70 waist may be of ordinary or any suitable construction, except that in the back or lower part thereof just above the buttons I form a vertical fold or plait 8 extending transversely across the waist. As shown in the 75 drawing, this fold is loose, except at its extremities where it is stitched through. Between these extremities the fold is free to open. Extending loosely across this fold are vertically disposed strips or bands 9 of 80 elastic material, as suspender webbing. As shown in the drawing, I have employed three of these elastic members, though the number may be varied as circumstances may require. Each of these elastic strips or members is 85 secured to the waist at its upper extremity, as shown at 10, and at its lower extremity, as shown at 19. Between these extremities the elastic member is loose and free to give as the position of the child may require, as 90 while bending forward, as illustrated in Fig. 5. When the waist is in use it is evident that as the child bends forward as illustrated in Fig. 5, the waist will extend, due to the fold 8 and prevent undue strain upon the buttons. 95

Having thus described my invention, what I claim is:

A child's nether-garment-supporting waist having a relatively narrow folded member set in the back of the waist with the fold 100

extending transversely of the entire back of the waist, the edges of said folded member being secured to the waist, elastic means spanning said folded member and secured to the waist immediately above and below the folded member, said elastic means extending and being effective throughout substantially

the entire transverse length of the folded member, and a series of fasteners on the garment below the folded member for the attachment of nether garments. 10

In testimony whereof I affix my signature.

EDNA F. MEIER.
